CLAIM

The ornamental design for a beach umbrella, as shown and described.

DESCRIPTION

FIG. 1 is a front and top perspective view of a beach umbrella, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of detail "8" identified in FIG. 1;

FIG. 9 is an enlarged view of detail "9" identified in FIG. 1; and,

FIG. 10 is an enlarged view of detail "10" identified in FIG. 1.

The dashed broken lines in the figures illustrate portions of the beach umbrella that form no part of the claimed design. The dash dot dash broken lines in FIGS. 1, 8, 9 and 10 are for the purpose of illustrating the enlarged views indicators and form no part of the claimed design.
